6 Claims. (Cl. 210—380)

This invention relates to a centrifugal drum with a solid casing for the separation of solid materials from liquid, for example of sugar crystals from sugar filling compositions, the casing of which is provided internally with a sieve.

In the case of large centrifugal drums it is difficult to achieve a uniform distribution of the filling mass applied to the drum wall. With known centrifugal drums the inner wall extends from the cover to the base at the same diameter. With centrifuged material, this construction leads to unfavourable swellings. These swellings, on the one hand, assist the pendulum motion of the centrifugal drum but on the other hand the centrifuging is irregular. Similarly, the washing of the centrifuged material in the centrifugal drum is made difficult thereby. These disadvantages are removed in accordance with the present invention by the feature that the centre part of the centrifugal drum in the delivery area of the centrifuged material has a smaller inner diameter than its axial end portions, and outlets for the centrifuged liquid are provided only in the bottom and cover of the centrifugal drum. This achieves the advantage that the swellings impeding a uniform centrifugal action are prevented from occurring on the centrifuged material so that, despite a greater depth of drum, no loss of throughput through the centrifugal drum occurs.

In a preferred embodiment of the invention the axial end portions of the drum casing are hollowed out in the form of rings on their inner side and the hollowed out annular spaces are filled with additional lower sieves. By this means the difference in the inner diameters on the centre portion and the axial end portions of the centrifugal drum can be accommodated in a simple manner. In another embodiment of the centrifugal drum a drum casing having a constant inner diameter is provided in the region of the delivery area of the centrifuged material with a ring reducing the inner diameter of the centrifugal drum at this point. This embodiment is particularly suitable for the subsequent arrangement of already existing centrifugal drums.

A further improvement is achieved in accordance with the invention by the feature that the outlets in the cover and bottom of the centrifugal drum and the outflow means for the liquid are located along the inner wall of the drum in alignment. By this means, the centrifuging of the liquid is facilitated because changes in the direction of the liquid are avoided.

In the accompanying drawings two embodiments of the invention are illustrated in which:

FIG. 1 shows an axial cross section of a large centrifugal drum,

FIG. 2 is an axial section through the drum of FIG. 1 on an enlarged scale, and

FIG. 3 is an axial fragmentary section through a second embodiment.

The embodiment shown in FIGS. 1 and 2 has a drum casing 1, a cover 2, a base 3 and a hub 4. The base 3

2

is screwed onto a flange 5 of the hub by screws 6. On the inner wall of the drum casing 1 is a lower sieve 7 which is closed by a cover sieve 8 on the inside. Two axial end portions 9 and 10 of the drum casing 1 are hollowed out in the form of rings. The hollowed out annular spaces 11 and 12 are filled with additional lower sieves 13 and 14. The sieves 7, 8, 13 and 14 are secured by coupling rings 15 in their position on the inner wall of the drum. The centre portion 16 of the drum casing has a smaller diameter than the axial end portions 9 and 10. The cover 2 is provided with outlet openings 17 and the base 3 with outlet openings 18 for the centrifuged liquid. The openings 17 and 18 are in alignment with the annular spaces 11 and 12. The delivery zone for the centrifuged material coincides with the centre portion 16 of the drum casing 1. The centrifuged material reaching this area flows upwardly and downwardly uniformly, bulges being avoided by the fact that the centrifuged liquid in the area of the delivery zone cannot flow outwardly through the drum wall. The discharge of the liquid along the inner wall of the drum is thereby prevented with the result that the delivered centrifuged material on the cover sieve 8 retains sufficient liquid to prevent bulging. At the points 19 and 20 of the axial end portions 9 and 10 the liquid experiences a greater centrifugal speed on account of the larger diameter of the drum casing 1 beginning at these points. Thus disintegration of the previously existing blockage and accelerated discharge of the liquid begins at the ends 25 of the centrifugal drum so that if a sufficient impediment to the fluid is maintained in the delivery areas 16, a faster throughput is achieved.

In the embodiment shown in FIG. 3 the reduction of the inner diameter of the centre portion of the drum is achieved by the feature that a ring 22 is inserted in the drum casing 21 having a constant inner diameter and it will be appreciated that this ring can also be introduced subsequently to manufacture of the drum. Moreover, this embodiment is constructed exactly as the embodiment shown in FIGS. 1 and 2.

What we claim is:

1. A centrifugal drum for the separation of solid material from liquids comprising an imperforate axially rotatable casing with centre and axial end portions, a base and a cover, a sieve fitting being carried internally of the casing over said centre and axial end portions, internal hollow rings in the form of recessed annular spaces defined by said axial end portions, additional lower sieves provided in said recessed annular spaces and outlet openings from the casing for outlet of separated liquid being provided only at the base and the cover, said recessed annular spaces and said outlet openings being in alignment and in communication with one another.

2. A centrifugal drum as claimed in claim 1 in which said centre and axial end portions are of unitary construction.

3. A centrifugal drum for separating a solid fraction from a liquid, comprising, in combination, an imperforate rotatable casing having axial end portions and a center portion of a lesser diameter than the diameter of said axial end portions; a base member and a cover member respectively associated with one of said end portions; a sieve fitting received within said casing and defining with said end portions a pair of annular spaces wherein the liquid is subjected to acceleration due to undergoing increased centrifugal force because of the larger diameter of said end portions; sieve elements received in

the respective annular spaces; and outlet means for separated liquid provided in at least one of said members.

4. A centrifugal drum as claimed in claim 3, wherein said sieve elements are of annular configuration.

5. A centrifugal drum as claimed in claim 3; and further comprising means for securing said sieve elements to said casing immovably relative thereto.

6. A centrifugal drum as claimed in claim 3, wherein said annular spaces and said outlet means communicate with one another and are in alignment.
